United States Patent Office

Des. 232,915
Patented Sept. 24, 1974

232,915

BOTTLE

Kurt Becker, Obernkirchen, Germ., assignor to
Hermann Heye, Obernkirchen, Germany

Filed Aug. 28, 1970, Ser. No. 24,746

Claims priority, application Germany Mar. 6, 1970

Term of patent 14 years

Int. Cl. D9—01

U.S. Cl. D9—135

Fig. 1

Fig. 2

Fig. 3

FIG. 1 is an elevational view of a bottle showing my new design, the opposite side being the same in appearance as the side shown;

FIG. 2 is a bottom plan view; and
FIG. 3 is a top plan view thereof.

I claim:

The ornamental design for a bottle, substantially as shown and described.
